UNITED STATES PATENT OFFICE.

JOHN J. GREEN, OF BRIDGEPORT, CONNECTICUT.

WHIFFLETREE-HOOK.

SPECIFICATION forming part of Letters Patent No. 275,196, dated April 3, 1883.

Application filed January 24, 1883. (No model.)

To all whom it may concern:

Be it known that I, JOHN J. GREEN, a citizen of the United States, residing at Bridgeport, in the county of Fairfield and State of Connecticut, have invented certain new and useful Improvements in Safeguards for Traces; and I do hereby declare the following to be a full, clear, and exact description of the invention, such as will enable others skilled in the art to 50 which it appertains to make and use the same.

My invention relates to that class of devices by means of which harness-traces are secured on the whiffletree, and has for its object to fasten a trace over the stud on the whiffletree, 55 so that it will be secure against all accidental displacement, while at the same time the device shall be simple in construction, economical in cost, and of ready adjustment; and with these ends in view my invention consists 60 in attaching to said whiffletree a lever so arranged as to swing in a plane at right angles to the plane of the stud on the end of the whiffletree, said lever having near its outer extremity a projection so situated that it will 65 shoot through the eye of the stud on the downward swing of said lever, all of which will hereinafter be fully described, and specifically 70 designated by the claim.

In order that those skilled in the art to 75 which my invention appertains may understand more fully how to make and use my improvement, I will proceed to describe the same in detail, referring by letters to the accompanying drawings, forming part of this specification, in which—

Figure 1 is a plan view of my device attached to an ordinary single-tree of a vehicle. Fig. 2 is a central vertical longitudinal section taken at the line $x-x$ of Fig. 1; and Fig. 3, a 80 plan view similar to Fig. 1, and showing the stud on the end of the single-tree in dotted lines.

Similar letters denote like parts in the several figures.

85 A is a single-tree, at the extremity of which is applied my improvement, which I have shown made in two parts, B C, the former secured to the tree, and the latter, which I style a "safeguard," hinged to the former in such 90 manner as to swing in the arc shown in dotted

lines at Fig. 2. At the extremity of the safeguard C is a projection, D, which, in the downward swing of said portion, shoots through the eye E of the stud F, for the purpose presently explained.

The application of my improved device is as follows: I apply the device as shown in the drawings, so that the projection D will, on the descent of the portion C, enter the eye E in the stud F. In attaching a trace to the tree I 55 simply lift the guard C, adjust the eye of the trace over the stud F, and let fall said guard, thereby securely confining the trace in the manner hereinbefore set forth.

Prior to my invention great danger and 60 annoyance have been experienced, owing to the continual slipping off of the traces from the stud on the tree; and, moreover, the devices as at present used for obviating this difficulty are very unreliable, especially when 65 leather strips are used, which are continually rotting or breaking away.

I am aware that various devices have been constructed for securing traces as against disengagement from the whiffletree-stud; but all 70 of these are of a spring nature, or are actuated by springs, which, by constant usage, lose their resiliency and become soft and malleable, thus rendering them entirely useless.

My improvement has nothing of a spring 75 nature, and the swinging portion, if accidentally dislodged from its position within the stud, will immediately drop back again by gravity.

Having thus described my invention, what I 80 claim as new, and desire to secure by Letters Patent, is—

In combination with the stud-eye F, the trace-guard made in two pieces, B C, the former secured to the whiffletree, and the latter hinged to the former and provided with projection D, substantially as shown and described.

In testimony whereof I affix my signature in presence of two witnesses.

JOHN J. GREEN.
